UNITED STATES PATENT OFFICE.

FRANK CURRENNTON SEARLE, OF WILMINGTON, DELAWARE.

BURIAL-VAULT.

1,024,527.

Specification of Letters Patent. Patented Apr. 30, 1912.

Application filed June 25, 1910. Serial No. 568,925.

To all whom it may concern:

Be it known that I, FRANK C. SEARLE, a citizen of the United States, residing at Wilmington, Newcastle county, Delaware, have invented certain new and useful Improvements in Burial-Vaults; and I do hereby declare the following to be a full, clear, and exact description of the invention, such as will enable others skilled in the art to 10 which it appertains to make and use the same.

This invention relates to certain improvements in and relating to burial vaults, and the like; and the objects and nature of my 15 invention will be readily understood by those skilled in the art in the light of the following explanation of the accompanying drawings illustrating what I now consider my preferred embodiment from among 20 other formations within the spirit and scope of my invention.

The invention consists in certain novel features in construction and in combinations and arrangements as more fully and particularly set forth hereinafter.

Referring to the accompanying drawings;—Figure 1, is a perspective view of the mold box with the casket box arranged therein, the parts being assembled in readiness to receive the concrete filling, the mold box being partially broken away to show one of the casket box supporting and centering devices. Fig. 2, is a longitudinal sectional view through the mold box placed in 35 the grave and containing the casket box showing the concrete filling. Fig. 3, is a cross section of the parts assembled and in a grave showing the concrete filling. Fig. 4, is a detail perspective view of one of the 40 casket box supporting and centering devices.

In the drawings, 1, is what I term a mold box or receptacle. This mold box is usually oblong in shape and open at the top with 45 closed or imperforate bottom, end and side walls. This box is usually strongly constructed of suitable sheet metal of the necessary large size to receive a casket box 2, and form a cement or concrete receiving space 50 completely around or inclosing the casket box. The casket box 2, is also strongly constructed, preferably of sheet metal, and is provided with an upwardly arched or dome-shaped slip cover 20, provided with top 55 loop handles 21. This cover is formed with a depending flange to fit down on the ex-

terior of the box, and the interior of the cover can be provided with suitable packing material 22, to fit the top edges of the box walls and form a fluid tight joint between 60 the box and cover. This casket box has closed or imperforate walls and the cover is also imperforate and the entire interior surfaces of the box and cover are preferably enameled or provided with any suitable impervious coating 23, to render the box absolutely tight. This box is designed to receive the coffin or casket when ready for burial, and when the box cover is applied, to tightly inclose and seal the casket against 70 entrance of cement or moisture to the interior of the box and to serve as a sustaining core box for the cement as hereinafter described, and an inner protecting inclosure for the casket.

Means are provided for centering the casket box 2, within the outer or mold box 1, and for supporting said casket box a distance above the bottom of said mold box. For instance, I show four rests, pillars or 80 supports 3, arranged on the bottom of the mold box and at the four corner portions thereof to receive the four corners of the casket box and maintain the casket box spaced from the side and end walls as well 85 as a distance above the bottom wall of the mold box. Each support 3, can be suitably bent up from sheet metal, or can be a casting or drop forging, or if so desired, can be formed of ceramic or other material, but is 90 preferably fixed to the floor of the mold box. If so desired, the supports can be formed of copper or other suitable non-corrosive metal. In the specific example illustrated, each support 95 is right-angled in formation with vertical walls having bottom feet or bases 30, resting on and secured to the floor, and at the required distance above said floor having inturned horizontal casket box supporting flanges or ledges 31, while the angularly arranged stop walls 32, project above the horizontal plane of the ledges 31, to engage vertical end and side walls of the casket box to maintain the box on the ledges 31 and 100 properly spaced or centered the required distances from the vertical walls of the mold box.

The mold and casket boxes are designed as articles of manufacture to be kept in stock by undertakers or funeral directors 110 and displayed in their show rooms, and hence are usually nicely finished and more

or less attractive in appearance as well as strong and durable in structure. When ready for burial, the coffin is placed in the casket box and the cover is properly applied thereto to tightly seal the same. The casket box is properly arranged on the supports in the mold box, the side and end walls of the mold box extending considerably above the horizontal plane of the casket box cover. The mold box with the casket box therein and containing the casket can then be lowered into the grave and the mold box is then completely filled with suitable grouting, cement, concrete or other suitable plastic material so as to entirely and completely inclose the casket box and form a seamless continuous sealing and inclosing wall between the bottom, sides and ends of the casket box and the corresponding walls of the mold box and entirely covering the casket box to the level of the top edges of the mold box. The loop handles of the casket box cover receive the plastic material and thus tie the cover thereto, and the arch cover of the casket box sustains the weight of the concrete thereon and causes the concrete thereon to set and harden in the form of a strong load sustaining arch. The casket box supports also form concrete reinforcing elements tending to tie the concrete walls together and to the box walls and at the same time holding the casket box properly centered until the concrete sets.

If so desired, the walls of the grave can be utilized as the mold to form the inclosing seamless shell of concrete around the casket

box of my invention, suitable end supports being provided to hold the casket box up from the bottom of the grave to permit the formation of the concrete wall thereunder. 40

The advantages of thus entirely inclosing the casket box in a seamless permanent shell or casing of concrete (and I use "concrete" in a broad sense to include any suitable plastic material) are obvious and well understood without elucidation. 45

What I claim is:—

1. In burial vaults, and the like, comprising mold boxes having supports on the floors thereof carrying casket boxes, each support 50 having an elevated ledge to receive a casket box and by which the casket box is held spaced from the floor of the mold box and vertical stop portions to hold the casket box centered on the support and spaced from the 55 vertical walls of the mold box.

2. In a burial vault, or the like, bottom corner supports for a casket box, each provided with elevated angularly arranged supporting flanges on which the bottom of the 60 box is adapted to rest with angularly arranged vertical stop walls adapted to engage the side and end walls of the box at the corners thereof to hold the box against lateral displacements. 65

In testimony whereof I affix my signature, in presence of two witnesses.

FRANK CURRINGTON SEARLE.
